United States Patent Office

Des. 216,436
Patented Jan. 6, 1970

216,436

PLATE OR SIMILAR ARTICLE

Elbert Welcome Mercer, Sugar Grove, Ohio, assignor to Anchor Hocking Glass Corporation, Lancaster, Ohio, a corporation of Delaware

Filed Jan. 9, 1969, Ser. No. 15,268

Term of patent 14 years

Int. Cl. D7—01

U.S. Cl. D44—15

FIG. 1 is a top plan view of a plate or similar article shown my new design;

FIG. 2 is an elevational view from the bottom of FIG. 1;

FIG. 3 is an elevational view from the right of FIG. 1; and

FIG. 4 is a sectional view on line 4—4 of FIG. 1.

I claim:

The ornamental design for a plate or similar article, substantially as shown.
